UNITED STATES PATENT OFFICE

173,089

BANANA CARRYING HARNESS

Walter A. Reich, Kansas City, Mo., assignor to
A. Reich & Sons, Inc., Kansas City, Mo., a corporation of Missouri

Application May 11, 1953, Serial No. 24,935

Term of patent 7 years

(Cl. D3—26)

To all whom it may concern:

Be it known that I, Walter A. Reich, a citizen of the United States, residing at Kansas City, in the county of Jackson and State of Missouri, have invented a new, original, and ornamental Design for a Banana Carrying Harness, of which the following is a specification, reference being had to the accompanying drawing, forming a part thereof.

Fig. 1 is a front perspective view of a banana carrying harness, showing my new design.

Fig. 2 is a rear elevational view thereof; and

Fig. 3 is a side elevational view of the banana carrying harness.

I claim:

The ornamental design for a banana carrying harness, as shown.
